SKIP HOIST EQUIPMENT

Filed Jan. 23, 1924

FIG. 1.

FIG. 2.

FIG. 3.

FIG. 4.

WITNESS:

Bob R. Kitchell.

INVENTOR

William E. Hale
BY
Augustus B. Strongton
ATTORNEY.

UNITED STATES PATENT OFFICE.

WILLIAM E. HALE, OF FORT WASHINGTON, PENNSYLVANIA, ASSIGNOR TO R. H. BEAUMONT COMPANY, OF PHILADELPHIA, PENNSYLVANIA, A CORPORATION OF PENNSYLVANIA.

SKIP-HOIST EQUIPMENT.

Application filed January 23, 1924. Serial No. 687,907.

To all whom it may concern:

Be it known that I, WILLIAM E. HALE, a citizen of the United States, residing at Fort Washington, in the county of Montgomery and State of Pennsylvania, have invented a new and useful Improvement in Skip-Hoist Equipment, of which the following is a specification.

Objects of the present invention are to insure proper clearance between the descending skip bucket and the pivotal loader gate, more especially in cases where the latter may shift or be shifted a little after having been put in closed position by the ascending bucket, to avoid any bumping action between the bucket and gate and to provide for smooth sliding contact between them, and other objects of the invention will appear from the following description.

The invention may be said to comprise a cam shoe device carried by one face of the bucket and projecting beyond the lower edge and toward the center line of the bucket to insure proper positioning of the gate to afford clearance for the passage of the descending bucket, with or without an outwardly sloping upper portion for shockless contact with the gate.

The invention further comprises the improvements to be presently described and finally claimed.

In the following description reference will be made to the accompanying drawings forming part thereof and in which—

Figure 1 is an elevational view of a skip bucket showing the cam shoe device applied to one face thereof.

Fig. 2 is an elevational view illustrating the gate in closed position.

Fig. 3 is a similar view showing the gate in open or loading position, and

Fig. 4 is a view similar to Figure 1 showing a portion of the gate and its hook or, in other words, it is a face view looking toward the left in Fig. 3.

In the drawings 1 is a cam shoe device carried by one face of the skip bucket 2, and it projects as at 3 beyond the lower edge and toward the center of the bucket.

The cam shoe 1 is shown as provided with an outwardly sloping upper portion 4. As shown the cam shoe device is duplicated and the parts are so spaced as to clear the hook 5 of the gate 6, Fig. 4. The hook 5 as shown includes two parts or sections connected by a spring 12 which acts as a cushion and permits the hook to elongate and contract. The gate 6 is pivoted to the chute 7 as at 8, and as usual is or may be counterweighted as at 13. The skip bucket 2 is made to ascend and descend on the skip hoist structure 9 for which purpose wheels 10 and a hoisting bale 11 are shown. There is nothing particularly new in the gate and skip bucket in themselves and they are subject to wide differences in form of embodiment.

The mode of operation may be described as follows:

In ascending the outwardly sloping upper portion 4 of the cam shoe device turns the gate upward in closed position, as shown in Fig. 2, in which position it is supposed to remain until the descending skip bucket 2, acting on the hook 5, turns it downward so that it comes into loading position as shown in Fig. 3. However, the gate does not always remain in turned up closed position but moves or is moved slightly downward out of that position and when that happens the inwardly projecting part 3 of the descending cam shoe device turns the gate upward into its proper position so that clearance is provided between it and the bucket, and the outwardly sloping upper portion 4 of the cam shoe device provides a means for smoothly diverting the gate from the bucket if the gate should tend to contact with the bucket after the part 3 has turned the gate upward and cleared it.

The invention is not limited to matters of mere form or otherwise than the prior art and the appended claims may require.

I claim:

1. Skip hoist equipment having in combination a pivotal loader gate, an ascending and descending skip bucket adapted to close and open the gate, and a cam shoe device

carried by one face of the bucket and projecting beyond the lower edge and toward the center line of the bucket to insure positioning of the gate to afford clearance for the passage of the descending bucket.

2. Skip hoist equipment having in combination a pivotal loader gate, an ascending

and descending skip bucket adapted to close and open the gate, and a cam shoe device carried by one face of the bucket and projecting beyond the lower edge and toward the center line of the bucket and provided with an outwardly sloping upper portion.

WILLIAM E. HALE.
